Primary Examiner — Abraham Bahta(74) *Attorney, Agent, or Firm* — C. Brant Cook(57) **CLAIM**

The ornamental design for a paper product with a pattern, as shown and described.

DESCRIPTION

FIG. 1 is a top plan view of a first embodiment of the paper product with a pattern showing my new design; and, FIG. 2 is a top plan view of a second embodiment of the paper product with a pattern.

The inner dash-dot-dot--dash broken lines show a boundary of the claim and forms no part of the claim.

All other broken lines are included for the purpose of illustrating environmental structure and forms no part of the claimed design.
